(57) **CLAIM**

The ornamental design for the antenna reflector, as shown.

DESCRIPTION

FIG. 1 is a perspective view of an antenna reflector showing our new design;

FIG. 2 is a front view of the antenna reflector of FIG. 1;

FIG. 3 is a rear view of the antenna reflector of FIG. 1;

FIG. 4 is a left view of the antenna reflector of FIG. 1;

FIG. 5 is a right view of the antenna reflector of FIG. 1;

FIG. 6 is a top view of the antenna reflector of FIG. 1; and,

FIG. 7 is a bottom view of the antenna reflector of FIG. 1.

The broken line showing of the mounting is for illustrative purposes only and forms no part of the claimed design.
